UNITED STATES PATENT OFFICE.

DAVID W. HAWKSWORTH, OF BIRMINGHAM, MICHIGAN, ASSIGNOR, BY MESNE ASSIGNMENTS, TO HUTCHINS CAR ROOFING COMPANY, OF DETROIT, MICHIGAN, A CORPORATION OF DELAWARE.

CAR ROOF.

Application filed October 26, 1925. Serial No. 64,905.

This invention relates to car roofs and more particularly to the construction of and the connection between, the junction cap and carline cap on the one hand and the running board saddle on the other.

The invention has one of its objects to provide a running board saddle having engagement, intermediate its length, with the junction cap, the engaging portions of these members being shaped to weatherproof the junction bolt, and to further provide means rigidly supported by the carline cap for supporting the running board saddle adjacent its ends.

The invention has also among its objects to simplify, render more efficient and improve generally constructions of this character, and the above as well as other objects, advantages and novel details of construction will be made more apparent as this description proceeds, especially when considered in connection with the accompanying drawings, wherein

Fig. 1 is a fragmentary top plan view of a car roof constructed in accordance with my invention,

Fig. 2 is a sectional view taken substantially on the plane indicated by line 2—2 in Fig. 1,

Fig. 3 is a vertical sectional view taken substantially on the plane indicated by 3—3 in Fig. 2, and

Fig. 4, 5, and 6 are fragmentary views similar to Fig. 2 showing modifications of the weatherproofing connection between the center joint cap and saddle.

Referring now particularly to the drawings wherein like reference characters indicate like parts, and more particularly to Figs. 1 to 3 thereof, it will be noted that there is illustrated a carline 10 extending transversely of the car roof and a ridge pole 11 extending longitudinally thereof, which parts are preferably secured together by means of bolts 12. The reference character 13 indicates the relatively movable roofing sheets, having upstanding flanges 14 at their sides which are weatherproofed by the carline caps 15 and also provided with upstanding flanges 16 at the ridge which are weatherproofed by the ridge caps 17.

Junction caps 18 are provided which fit the adjacent ends of the carline and ridge

caps 15 and 17 respectively for weatherproofing the car roof at these junction points, and arranged between each junction cap and the adjacent end of the carline and ridge caps is a washer 19 preferably of flexible material such as canvas or the like, and also preferably impregnated with some weatherproofing material.

Extending vertically downwardly through each junction cap 18 is a junction bolt 20, this bolt extending through the ridge pole and adjacent carline and being engaged by a suitable nut 21 for securing the junction cap in place. The bolt 20 is provided with a shoulder 22 which engages the under side of junction cap 18 and the bolt is rigidly secured to this junction cap by riveting the head 23 thereof. Thus the head of the bolt is exposed.

The running board saddle is indicated generally by the reference character 24 and rests upon and is supported by the junction cap 18, which for this purpose is provided with a horizontally arranged embossed upwardly extending portion 25. The running board saddle is formed with a concavo-convex portion 26 adapted to surround and embrace the bolt head 23 and by reason of the engagement between the saddle and the embossed portion 25 of the junction cap, to weatherproof this bolt head.

The running board saddle is rigidly held in place and additionally supported adjacent its outer ends by means of shoulder bolts 27 riveted to the carline caps 15. These shoulder bolts are preferably riveted at upwardly embossed portions 28 of the carline caps with washers 29 interposed between the head and shoulder of the bolt and the body of the carline cap. The saddle 24 is preferably provided adjacent each end with a centrally arranged depressed portion 30 inclined and arranged substantially parallel to the adjacent carline cap 15. Each depressed portion 30 is formed preferably with an enlarged opening or slot 31 through which the end of the adjacent shoulder bolt 27 is adapted to extend. Co-operating with each shoulder bolt is a nut 32 and a lock washer 33 whereby the saddle 24 may be securely fixed in place. By providing the slots or enlarged openings 31 variations in the size of the parts and in the

positioning of the shoulder bolts 27 may be compensated for.

The saddle is provided with horizontally extending portions 34 for supporting the running boards 35 which are preferably secured thereto by bolts 36. The construction of the running board saddle 24 is such that it may be pressed from sheet metal.

In Fig. 4 the junction bolt 20^a is formed without the shoulder portion 22 but is provided with an exposed head 23^a which is surrounded and embraced by the concavo-convex portion 26 of the running board saddle 24 as in the previously described construction. However, it is preferable in this present construction to insert between the head 23^a and the embossed portion 25 of the junction cap 18, a lead washer 37. Furthermore, the bolt 20^a is preferably provided with the squared portion 38 cooperating with a similar shaped aperture in the junction cap 18 whereby rotation of the bolt 20^a is prevented and the tightening of the nut 21 facilitated. In other respects this construction is substantially similar to the one previously described.

In Fig. 5 the junction cap 18 is provided with an upwardly extending embossed portion 25^a of a relatively smaller area and so selected as to project in inter-engaging relation with the concavo-convex portion 26 of the saddle 24. In this form of construction the bolt is provided with a head 23^a as in the construction described immediately previous and a lead washer 37 is interposed between this head and the embossed portion 25^a. By the construction illustrated in Fig. 5 a more efficient weatherproofing of the bolt 20^a is effected.

In Fig. 6 the embossed portion 25^b of the junction cap 18, corresponding to the previously described embossed portions 25 and 25^a, is formed with an upstanding flange 39 immediately surrounding the aperture through which bolt 20^a passes. The head 23^a of this bolt rests on this upstanding flange 39, and this bolt head is surrounded and embraced by the concavo-convex portion 26 of the running board saddle 24 as in the previously described construction. However, in the present construction it has been found desirable to arrange a canvas or lead washer 40 between the engaging portions of the junction cap and the running board saddle, this washer surrounding the upstanding flange 39 and resting upon the embossed portion 25^b.

From the foregoing it will be apparent that various means may be employed for weatherproofing the junction bolt by utilizing the engagement between the running board saddle and the junction cap and by properly shaping these parts adjacent their engaging portions. Furthermore, means are provided for additionally supporting the running board, this construction offering the

possibility of assembling the parts with ease and facility.

While several illustrative embodiments of the invention have been described and illustrated herein somewhat in detail, it will be readily apparent to those skilled in this art that various changes and modifications may be resorted to without departing from the spirit and scope of this invention and to this end reservation is made to make such changes as may come within the purview of the accompanying claims.

What I claim as my invention is:

1. In a car roof, the combination with a carline cap, of a running board saddle, spaced means carried by said carline cap for supporting said saddle and a portion formed on said saddle adapted for adjustable engagement with said supporting means.

2. In a car roof, the combination with a carline cap, of a running board saddle, and fixed means carried by said carline cap and engageable in slots in said saddle for supporting the latter.

3. In a car roof, the combination with a carline cap, of a running board saddle, and means carried by said carline cap and engageable in openings in said saddle for supporting the latter, the said openings being enlarged to permit an adjustment of the saddle relative to the said supporting means.

4. In a car roof, the combination with a center joint cap and bolt, and a carline cap, of a running board saddle engaging said center joint cap for weatherproofing said bolt, and means fixed to said carline cap for supporting said saddle adjacent the ends thereof.

5. In a car roof, the combination with a center joint cap and bolt, and a carline cap, of a running board saddle, engaging said center joint cap for weatherproofing said bolt, and fixed means carried by said carline cap and engageable in slots in said saddle for supporting the latter.

6. In a car roof, the combination with a center joint cap and bolt, and a carline cap, of a running board saddle engaging said center joint cap for weatherproofing said bolt, and bolts riveted to said carline cap and engaging said saddle for supporting the latter.

7. In a car roof, the combination with a center joint cap and bolt, and a carline cap, of a running board saddle engaging said center joint cap for weatherproofing said bolt, and shoulder bolts rigidly fixed to said carline cap and engageable in openings in said saddle for supporting the latter.

8. In a car roof, the combination with a center joint cap and bolt, and a carline cap, of a running board saddle engaging said center joint cap for weatherproofing said bolt, shoulder bolts riveted to said carline cap and passing through said saddle with

the shoulder thereof engaging said carline cap and saddle and a nut engaging said bolt for securing said saddle thereto.

9. In a car roof, the combination with a center joint cap and bolt, and a carline cap, of a running board saddle engaging said center joint cap, the engaging portions of said members being shaped to provide weatherproofing means for said bolt, and shoulder bolts projecting upwardly from said carline cap and engaging said saddle for supporting the latter.

10. In a car roof, the combination with a center joint cap and bolt, and a carline cap, of a running board saddle engaging said center joint cap, intermediate its length, the engaging portions of said members being shaped to provide weatherproofing means for said bolt, and shoulder bolts projecting upwardly from said carline cap and engaging said saddle for supporting the latter adjacent its ends.

11. In a car roof, the combination with a center joint cap and bolt, and a carline cap,

of a running board saddle engaging said center joint cap, the engaging portions of said members being shaped to provide weatherproofing means for said bolt, and shoulder bolts projecting upwardly from said carline cap and engaging openings in said saddle for supporting the latter.

12. In a car roof, in combination, a carline cap, a running board saddle formed with slots opening at the ends thereof and means carried by said carline cap and engageable in said slots for supporting said saddle.

13. In a car roof, the combination with a carline cap, of a running board saddle and shoulder bolts carried by said carline cap for supporting said saddle.

14. In a car roof, the combination with a carline cap, of supporting members carried by the said carline cap, and a running board saddle adjustably engageable with the said supporting members.

In testimony whereof I affix my signature.

DAVID W. HAWKSWORTH.
